UNITED STATES PATENT OFFICE.

JUDSON SHOECRAFT, OF TOPEKA, AND CHARLES C. GARDINER, OF BRADFORD, KANSAS; SAID SHOECRAFT ASSIGNOR TO SAID GARDINER.

ELECTRICAL SEMAPHORE SYSTEM.

SPECIFICATION forming part of Letters Patent No. 658,929, dated October 2, 1900.

Application filed June 20, 1899. Serial No. 721,239. (No model.)

To all whom it may concern:

Be it known that we, JUDSON SHOECRAFT, residing at Topeka, in the county of Shawnee, and CHARLES C. GARDINER, residing at Bradford, in the county of Wabaunsee, State of Kansas, citizens of the United States, have invented a new and useful Electrical Semaphore System, of which the following is a specification.

10 This invention relates to electrically-operated railway-signals, and more particularly to that class known as "semaphore-signals," one object of the invention being to provide a block-signal system, which is electrically operated and which involves, in addition to the usual arrangement of a signal at each end of the block, the employment of supplementary signals at a specified distance from each end of the block and exteriorly thereof, although 20 in practice the supplemental signals may be employed or discarded, as desired.

Another object of the invention is to provide a system involving but three wires, of which one is a common return for two separate 25 sources of electricity from which two distinct sets of apparatus are energized, the circuits of these sets of apparatus being closed through a common relay when the latter is energized.

A further object of the invention is to provide a simple and effective electromechanical apparatus for raising and lowering the semaphore-arms under certain specified conditions.

Other and further objects of the invention will be evident in the following description.

35 In the drawings forming a portion of this specification, and in which like numerals of reference designate corresponding parts, Figure 1 is a diagrammatic representation of a block protected by a system and apparatus 40 involving this invention. Fig. 2 is a detail elevation of the semaphore-operating apparatus and an adjacent semaphore connected therewith, the apparatus being in a position to be released to set the semaphore at "danger." Fig. 3 is a view similar to Fig. 2, showing the 45 semaphore set at "danger" and the position of the operating mechanism at the same time. Fig. 4 is a view similar to Fig. 3, showing the 50 semaphore lowered and the position of the parts of the lowering mechanism just previous to the breaking of the circuit of the elec-

tric motor included in said mechanism. Fig. 5 is a side elevation of Fig. 4 looking from the left. Fig. 6 is a detail perspective of the split nut and connected mechanism. Fig. 7 55 is a detail section of the split nut and trip-lever carried thereby, portions of said lever being in elevation. Fig. 8 is a perspective view of the cam-shaft, to which the trip-lever is connected. Fig. 9 is a detail view showing the location of the striking-nut and its jam-nut upon the reciprocating rod.

Referring now to the drawings, as above intimated, this system involves a plurality of 65 duplicate semaphore-operating mechanisms in combination with sources of electricity and means for closing the circuits of the several elements of the mechanisms. This semaphore-operating mechanism is attached directly to the semaphore-post 10, and consists 70 of a base-plate 11, upon which is mounted a frame 12, having a central perforation, vertically of which is passed the screw-threaded shaft 13 of an electric motor 14, located below the base 11 and held in proper position upon 75 the semaphore-post. This shaft 13 may constitute the armature-shaft of the motor, or, if preferred, may have suitable bearings in the base 11 and in a diamagnetic plate 15, secured to the motor, and may have mounted 80 thereon, beneath the base 11, a gear-wheel 16, meshing with the pinion 17 upon the armature-shaft, as shown. Thus as the armature of the motor rotates the shaft 13 will be rotated, and from the rotation of this shaft the 85 semaphore mounted upon the post 10 is lowered.

Slidably mounted in the upper portion of the frame 12 and centrally thereof is a rod 18, the upper end of which has a link connection 90 19 with a lever 20, fulcrumed upon the post 10, and from the work end of which lever extends a reciprocating rod 21, pivoted at its upper end to a semaphore-arm 22 in the usual manner, and which arm has at its rear end 95 on the inner side of the post a lens 23, adapted to coöperate with a lantern 24 to give visual signals at night. The lower end of the rod 18 enters the inclosure of the frame 12, and has mounted thereon a block 25, on opposite sides of which are secured the upper 100 ends of diverging hangers 26, of spring mate-

rial, having fixed to their lower ends the sections 27 and 28 of a transversely-split nut, the screw-threaded perforation of which is adapted to engage and fit upon the threads 5 of the shaft 13, whereby when the nut is in a closed position the rotation of the shaft 13, through the medium of the armature of the motor 14, will act to feed the nut longitudinally of the shaft and move the semaphore-arm 22 upon its pivot. In this construction it is intended that the rotation of the screw-shaft 13 will be in a direction to move the nut upwardly, and thus to lower the semaphore-arm into what is known as the "safe" position. When the nut has been fed to the limit of its upward movement, the motor-circuit is broken, and subsequently under certain conditions the nut is open to release the screw, when the weight of the parts, together with 20 the weight 29 upon the rear end of the semaphore-arm, will act to drop the nut and to raise the semaphore-arm to the danger position.

The spring quality of the hangers 26 acts to 25 normally hold the split nut open and out of engagement with the shaft 13. In order to draw the parts of the nut together and hold them upon the shaft 13, there is secured to the opposite ends of the nut-section 27 plates 30 31 and 32, which inclose the ends of the nut-section 28, and with which plates the section 28 is in slidable contact. The plates 31 and 32 extend beyond the outer face of the section 28 and of the adjacent hanger, and in 35 bearings in the protruding portions of said plates is journaled a shaft 33, having thereon a cam 34^a, which in one position of the shaft bears against the adjacent face of the nut-section 28 and moves it in the direction of 40 the section 27 to grasp the threaded shaft 13 and operatively engage it. In order to hold the cam at times in this position, a trip-lever 34 is fixed to a protruding end of the shaft 33, and which lever is provided at one end 45 with a weight 35, adapted to be passed over and from one side to the other of the shaft 33 to correspondingly move its opposite upwardly-curved and broadened end 36. This reciprocatory movement of the weighted end 50 of the lever acts to throw the cam 34^a into and out of engagement with the nut-section 28, as above specified.

When the split nut is in the position shown in Fig. 3 of the drawings, the weighted end of 55 the lever is in a position to hold the cam against the adjacent nut-section to engage the nut-sections with the shaft 13. If the motor be then energized, the nut will move upwardly of the shaft until it has reached the upper limit of its 60 movement, when the nut will be disengaged from the shaft by the swinging of the weighted lever to its opposite position. (Shown in Fig. 2 of the drawings.) In order to swing the lever, as mentioned, there is fixed to the block 25 a 65 spring-plate 38, having an opening 39 therein, through which projects the end of a finger 59, the opposite end of which is pivoted to a

standard 40 and has connected therewith, adjacent its pivot, a helical spring 41, the opposite end of which is attached to a projection 70 of the standard 40. This spring tends to hold the finger in a lowered position, while the upward movement of the plate 38, under the influence of the split nut, raises the free end of the finger and places the spring 41 under tension. The upwardly-curved end of the lever 34 lies with its broadened portion in the path of movement of the finger 49 as the nut moves upwardly, as shown in Fig. 4 of the drawings. Hence when the nut has moved 80 upwardly a distance sufficient to draw the finger from the opening in the plate 38, which is just prior to the nut reaching the upper limit of its motion, the finger 59 will descend under the influence of its spring and 85 engaging the adjacent end of the lever will throw it downwardly and will rock the weighted end 35 thereof over the shafts 33 to move the cam 34 from the nut-section 28 and cause the nut to disengage the screw-shaft, when 90 the nut and the mechanism connected therewith will drop and the semaphore-arm will be raised to the danger position. In order to arrest the drop of the nut before it has reached the limit of its downward motion and before 95 the semaphore is set at "danger," so that it may be quickly released to continue its downward movement to set the semaphore, a lever 50, pivoted in the side of the frame 12, has a foot 51, adapted to project into the path of the nut-section 27 in its descent and to receive and hold the nut in the position mentioned. When the nut-section 27 strikes the foot 51, it is temporarily held against further downward movement, and just previous to arriving at this position the circuit, including 100 the motor 14, is broken to prevent further operation of the motor. This breaking of the motor-circuit is accomplished through the medium of a cam 52 upon the shaft 33 and which cam, as the nut ascends, is out of line with a projection 53 of one terminal 54 of the motor-circuit and which terminal is adapted to normally engage a second terminal 55, which is fixed with respect to the frame 12, the terminal 54 being of spring material. When the lever 34 is thrown by the finger 59, the cam 105 52 is rotated to a position to engage the projection 53 as the nut descends, which engagement, as above mentioned, is just previous to 110 the engagement of the nut-section 27 with the foot 51. Hence when the section 27 is resting upon the foot 51 the circuit of the motor 115 is broken and the mechanism is at rest.

In order to hold the foot 51 in engagement 120 with the element 27, the lever 50 is continued outwardly of the frame 12 and is connected at its outer end with the armature 55 of an electromagnet 56, which when energized holds the armature in a position to project the foot 125 into the path of the nut-section 27, the proportions of the parts being such that when the circuit of the electromagnet is broken the armature will rise and the weight of the nut 130

and connected mechanism upon the foot 51 will act to swing the lever 50 upon its pivot and move the foot out of the path of the nut. The nut will then immediately drop to the lower limit of its movement and the contact-piece 54 will rise to the contact 55, and if the circuit of the motor be otherwise closed the motor will at once begin to operate.

When the nut has reached the limit of its downward movement, it is of course necessary to reengage the nut-sections with the shaft 13, and for this purpose the end of the lever opposite the weight 35 is arc-shaped, and thus by striking the base 11 the extremity of the lever will be rocked slightly upwardly until the weight 35 has passed over the shaft 33, when the weight will act to further rock the shaft and close the nut upon the shaft 13.

In order to insure the dropping of the nut to the proper point each time, so as to fairly engage the threads of the shaft 13, the lower end of the rod 18 is threaded and has a stop-nut 16 engaged therewith, a suitable set-nut 25 being also disposed upon the rod to hold the nut 60 in position. This nut 60 is held by the rod 18 directly over the upper end of the shaft 13, so that when the split nut is dropped this nut 60 will strike upon the upper end of 30 said shaft, and thus limit the fall of the split nut. By adjusting the nut 60 upon the rod 18 the fall of the split nut may be so regulated that when the sections of the split nut come together their threads will properly engage the threads of the shaft.

In practice the motor and the electromagnet have individual batteries, the circuits of which include a common return, and in which return is arranged a relay make-and-break apparatus, and thus may the circuits of the motor and the electromagnet, which forms, in effect, an electromagnetic lock, be simultaneously closed or broken through the medium of a single circuit including the relay. Also it will be seen that the circuits of the motor and electromagnet will both remain closed when the relay is in a proper position from the time the nut leaves the foot 51 until it has been again raised and dropped to said foot. In other words, as will be understood from the foregoing description, the semaphore-setting apparatus will stand normally in a position to drop the nut and raise the semaphore-arm. If the nut be dropped and the motor-circuit be then closed, the motor will operate to lower the semaphore-arm and will continue to rotate until the nut has moved to the limit of its upward movement and is then dropped to its normal position, as shown in Fig. 2.

Referring now more particularly to Fig. 1 of the drawings, it will be seen that there has been represented a block comprising rails 70 and 71, the ends of the sections of rails forming the block being insulated from the rails of the block at either side. Connected across the rails 70 and 71 is a battery 72, and con-

nected also across the rails is a relay 73^a, the relay being thus in direct circuit with the battery, from which it will receive energy so long as the circuit be unbroken or be not short-circuited.

In the drawings there is shown no means for breaking the circuit, but instead it will be readily seen that upon the entrance of a train upon the block including the rails 70 and 71 the wheels and connecting-axles of a car or cars will act to short-circuit the battery 72, and thus to de-energize the relay 73^a. As shown in Fig. 1 of the drawings, this system involves a semaphore located adjacent each end of the block and an additional or supplementary semaphore arranged a predetermined distance in advance of the adjacent end of the block. These semaphores are each equipped with the apparatus above mentioned, the electromagnets of the several mechanisms being connected in series with a battery 73 through the armature 74 of the relay. A battery 75 is provided for the motors and with which battery said motors are connected mutually in multiple arc, the circuit of the battery 75 including the armature 74 of the relay in common with the circuit of the electromagnets. The circuit of the electromagnets will be as follows: battery 73 to magnet 156, to common conductor 76, to magnet 256, to common conductor 77, to relay-armature 74, to conductor 78, to conductor 79, to conductor 80, to conductor 81, to magnet 356, to conductor 82, to magnet 456, to conductor 83, to conductor 84, to conductor 85, to conductor 86, to battery 73, conductor 79 being a common conductor, as will be presently seen.

One terminal of motor 114 is connected with the positive terminal of battery 75 through conductor 87 and conductor 88, the opposite terminal being connected with the opposite terminal of the battery 75 through the common conductor 78, relay-armature 74, common conductor 77, conductor 89, and common conductor 76. The motor 214 has one terminal connected with the conductor 89 and the other with the conductor 87, thus being parallel with the motor 114 and in series with the battery 75. The motor 314 has one terminal connected with the positive terminal of the battery 75 through conductors 90, 91, 92, 79, and 93, the opposite terminal of the motor being connected through connections 94, 95, 96, and 97 with the relay 73^a, and thence through armature 74 and conductor 78 to conductor 98 and negative terminal of the battery. The motor 414 has one terminal connected with the conductor 80, which is connected with the similar terminal of the motor 314 and has its opposite terminal connected with the conductor 95, with which the corresponding terminal of the motor 214 is connected through the conductor 94, it being thus seen that both motors 314 and 414 are mutually in parallel or multiple arc and are similarly connected with the motors 114 and 214.

Upon reference to the above description

and the accompanying drawings it will be seen that when the block comprising the rails 70 and 71 is free the full force of battery 72 will be applied to the relay, which in attracting its armature will close the circuits of batteries 73 and 75 through their respective translating devices, causing the motor to operate the screw-shaft 13 and the foot 51 to be projected or held in its projected position.

10 At this time the sections of the split nut will lie in engagement with the threads of the screw-shaft, due to the outward position of the rod or lever 34, causing the cam 52 to engage the spring-piece 26 and move its nut-section 28 in the direction of the nut-section 27. The foot 51 will be held projected and the motor will be maintained in operation, causing the split nut to rise, and thus move the semaphore downwardly to the safe position.

15 While the split nut is moving upwardly, the finger 59 is lying in the opening 39. When the split nut has been moved to near the upper limit of its motion, the spring-plate 38 is moved from the finger 59, which passes from the opening 39 and under the influence of the spring 41 moves quickly downwardly and strikes the broadened end 36 of the lever 34, the strength of the spring being such as to depress this broadened end and to 20 move the weight 35 over the shaft 33, and thus move the cam 52 from the plate 26, the weight 35 holding the shaft 33 and its cam in this position. When the cam 52 is drawn away from the plate 26, the spring quality of 25 the latter causes it to move outwardly and draw its nut-section 28 from engagement with the threads of the shaft 13. The spring quality of the opposite plate 26 causes it at the same time to move outwardly and carry its

30 nut-section 27 away from the threads of the shaft. When these nut-sections are thus moved, the split nut and the mechanism carried thereby drops and the nut-section 27 rests upon the foot 51, as shown in Fig. 2 of the drawings. In the passage of the split nut to rest upon the foot 51 the nut-section 28 drops upon the projection 53 of one terminal 35 of the motor-circuit and moves that terminal away from its opposing terminal 55 to

35 break the motor-circuit and stop the operation of the motor. So long as the block in the track is open the relay will continue energized and will maintain the circuit of the electromagnets 56 to hold the foot 51 projected.

40 If now a train enters upon the block, the relay is at once short-circuited, and the energization of the electromagnet 56 is annihilated through the breaking of its circuit, allowing the foot 51 to swing rearwardly, under the influence of gravity, of the split nut and its connection, so that the foot will release the split nut and allow it to drop, drawing the rod 18 downwardly and setting the 45 semaphore at "danger." The continuation of the motor-terminal against which the split-nut section 28 rests is not of sufficient stiffness to support said nut-section, and it is

therefore pressed out of the way temporarily and then rises and engages the opposing terminal to close this portion of the motor-circuit. The armature of the relay being in the motor-circuit, however, the motor will receive no current until the short circuit of the relay-battery has been removed, or, in other words, until the train has passed from the block. This dropping of the split nut and the mechanism carried thereby causes the end of the lever 34 to strike upon the plate 11, with the effect of rocking the shaft 33 and throwing the weight 35 over the shaft to move the cam 52 to clamp the nut-sections upon the motor-shafts. Thus the parts of the apparatus are ready for operation to lower the semaphore as soon as the train passes from the block.

45 As shown in Fig. 1 of the drawings, the semaphore and its operating mechanism at each point is so connected with the other mechanisms and with the batteries that there will be a simultaneous movement of the different mechanisms and a similar movement of the semaphores. Thus the semaphores will simultaneously indicate danger or will indicate a clear track.

50 In practice the supplemental signals, which are the outermost signals shown in Fig. 1 of the drawings, are positioned a predetermined distance beyond their respective ends of the block, and if this distance be one thousand feet the engineer in reaching the supplemental signal will be warned at least a thousand feet in advance of the block as to the condition of the block, the semaphore-arms of the supplemental signal having any desired distinguishing characteristics. In the usual arrangement when the engineer gains sight of a signal and sees it set at "danger" he is unable to tell whether the train in the block is at the opposite end of the block or whether it is within a few hundred feet of him. With this arrangement, however, if the engineer sees the supplemental signal set at "danger" he knows that the block ahead is occupied and he has at least one thousand feet in which to stop and back out, thus eliminating the greatest danger in a block system.

55 It is of course understood that the foregoing description has reference to a single-track railway and also that the mechanism described and the principles involved may be applied to a double-track railway; also, that the specific construction and arrangement shown and described may be varied without departing from the spirit of the invention and that the mechanisms for operating the different semaphores may be fixed within suitable casings to facilitate the application and removal of them, the drawings showing the reciprocating rod 21 provided with an inclosing tube leading from the top of an inclosing casing to the housing of the crank of the semaphore-shaft or other connection with the semaphore. It will furthermore be seen that each supplemental signal has a three-wire connec-

tion with its respective main signal, while the main signals have themselves three wire connections with the central station in which the relay and batteries are located. The central 5 may be located at any desired point, preferably adjacent the block.

Having thus described the invention, what is claimed is—

1. A signal system comprising a number of 10 signals each having an operating mechanism, and each mechanism comprising a motor for actuating the signal and a locking-magnet for holding the signal against movement, a source of electricity with which the motors are connected in multiple, a separate source of electricity with which the magnets are connected in series, the circuits of the two sources of electricity including a common conductor, and a track-relay for opening and closing the 15 common conductor.

2. A signal system comprising a number of 20 signals, each having an operating mechanism, and each mechanism comprising a motor for actuating the signal and a locking-magnet for holding the signal against movement, a source of electricity with which the motors are connected in multiple, a separate source of electricity with which the magnets are connected in series, the circuits of the two sources of 25 electricity including a common conductor, a relay for opening and closing the common conductor, said relay having its winding terminals connected with opposite insulated rails of a trackway, a battery for the relay 30 having its terminals connected with said rails, and a circuit-breaker in the local circuit of each motor, said circuit-breaker being operated and held operative by that portion of the mechanism that is held by the locking- 35 magnet, whereby when the locking-magnet circuit is broken at the relay, the circuit-breaker will be released to close the local circuit of the motor.

3. The combination with a semaphore, of 40 a follower connected therewith, electrically-operated means for moving the follower to move the semaphore in one direction, means for releasing the follower and subsequently breaking the motor-circuit, means for holding the 45 follower intermediate the limits of its motion, means for releasing the follower to allow it to reach the limit of its continued movement, and means for throwing the follower into operative relation with its moving means.

55 4. The combination with a semaphore, of a follower connected therewith, and having a definite path of movement, electrically-operated means for moving the follower in one direction to the limit of its movement, means 50 for releasing the follower at said limit of movement, means in the path of the follower for engagement thereof in its opposite movement to break the circuit of its moving mechanism, means for supporting the follower to hold the 55 circuit broken, means for releasing the follower, means for simultaneously breaking the circuit of the moving means, and means

for subsequently throwing the follower into operative relation with the moving means.

5. The combination with a semaphore of an 60 electric motor, a circuit including said motor a screw-shaft adapted for rotation by the motor, a follower adapted to move alternately with and independently of the screw-shaft, connections between the follower and the 65 semaphore, and a circuit-breaker for breaking the motor-circuit, said circuit-breaker being adapted for operation by engagement of the follower.

6. The combination with a semaphore, of 70 an electric motor, a screw-shaft adapted for rotation by the motor, an electric circuit for the motor, a follower adapted for engagement and disengagement with the screw-shaft to move alternately with and free thereof, 75 means in the path of the free movement of the follower for opening the motor-circuit, means for holding the follower to maintain said circuit open, and means for releasing the follower to permit closing of the circuit. 80

7. The combination with a semaphore, of 85 an electric motor, a screw-shaft adapted for rotation by the motor, an electric circuit for the motor, a follower adapted for engagement and disengagement with respect to the screw- 90 shaft to move alternately with and free thereof, a circuit-breaker in the motor-circuit, an adjustable striker carried by the follower and adapted to engage and operate the circuit-breaker in one direction of movement of the 95 follower, means for holding the follower in its operative relation to the circuit-breaker, means for releasing the follower to release the circuit-breaker, and means for breaking the circuit of the motor at a different point subsequent to the closure of the circuit-breaker. 100

8. The combination with a semaphore, of 105 an electric motor, a screw-shaft adapted for rotation by the motor, an electric circuit for the motor, a follower adapted for alternate engagement and disengagement with respect to the screw-shaft to move with or free thereof, a movable striker carried by the follower adapted for alternate projection and retraction, a circuit-breaker in the motor-circuit 110 adapted for engagement by the striker in one direction of movement of the follower, means for holding the striker in operative relation to the circuit-breaker, and a common means for releasing the striker to release the circuit-breaker and for breaking the circuit to the 115 motor at a different point.

9. The combination with a semaphore, of 120 an electric motor, a screw-shaft adapted for rotation by the motor, an electric circuit for the motor, a follower connected with the semaphore and adapted for engagement and disengagement with respect to the screw-shaft to move alternately with and free thereof, a circuit-breaker in the motor-circuit, a movable 125 striker carried by the follower and adapted to engage and operate the circuit-breaker in one direction of movement of the follower, electromagnetic means for holding the fol- 130

lower in its operative relation to the circuit-breaker, an electric circuit for said electro-magnetic means, and a common relay for the circuits of the motor and the electromagnetic means adapted to break said circuits subsequent to the engagement of the striker with the circuit-breaker.

10. The combination with a semaphore, of an electric motor, a screw-shaft rotatably connected with the motor, an electric circuit for the motor a circuit-breaker in the motor-circuit, a follower connected with the semaphore and adapted for alternate engagement and disengagement with respect to the screw-shaft 15 to move alternately free of and with the shaft, a shaft carried by the follower, a striker carried by said shaft and adapted to be moved into and out of operative relation with the circuit-breaker, means for holding the striker 20 with the follower in operative relation to the circuit-breaker, means for releasing the follower to move the striker from the circuit-breaker, a weighted lever upon the striker-shaft adapted to lie on opposite sides of its 25 center of gravity to alternately project and retract the striker, connections with said lever for alternately throwing the follower into and out of engagement with the screw-shaft, and means for moving the lever.

30 11. The combination with a semaphore, of an electric motor, a screw-shaft adapted for

rotation by the motor, an electric circuit for the motor, a follower connected with the semaphore and adapted for engagement and disengagement with respect to the screw-shaft 35 to move with or free thereof, a circuit-breaker in the motor-circuit, a shaft carried by the follower, a striker carried by said shaft and adapted to engage and operate the circuit-breaker at times, means for holding the follower with the striker in operative relation to the circuit-breaker, means for releasing the follower to move the striker from operative relation to the circuit-breaker, a weighted lever connected with the striker-shaft and 40 adapted to lie on either side of its center of gravity to project or retract the striker, means carried by the striker-shaft for engaging the follower with the screw-shaft when the striker is retracted, a spring-finger adapted to engage 45 the weighted lever and throw it from one side to the other of the center of gravity, and means carried by the follower for energizing said finger.

In testimony that we claim the foregoing as 55 our own we have hereto affixed our signatures in the presence of two witnesses.
